LOCK KNIFE FOR HARNESS MECHANISM

Application filed January 23, 1931. Serial No. 510,732.

This invention relates to improvements in lock knives for so-called Knowles heads and it is the general object of the invention to provide means whereby such a knife will be given positive movements both toward and from vibrator lever locking position.

The so-called Knowles head operates with a set of vibrator levers which are located between upper and lower oppositely rotating mutilated cylinder gears. Each lever is operatively related to one or another of these cylinders for each pick of the loom, the operating position being determined by the pattern chain. It occasionally happens that a vibrator lever will be lifted by its adjacent levers because of friction although there is no pattern ball under it with the result that a lever so lifted will not be high enough to be properly engaged by the top cylinder. Under these circumstances the vibrator gear will be pushed downwardly but not in sufficient time to receive the complete movement of the lower cylinder, with the result that the harness jack is not definitely positioned. It is an important object of my present invention to provide a lock knife somewhat similar to that heretofore employed for the purpose of positioning the vibrator levers, but so actuated that if a lever be raised partially it will be given a downward movement in time to receive the complete rotative effect of the lower cylinder. Heretofore springs have been employed to operate the lock knives toward the vibrator levers with resultant yielding of the knife permitting the vibrator lever to remain in its improper position.

It is another object of my invention to improve the operating connections between the lock knife and its actuating cam, these connections permitting vertical adjustment of the lock knife with respect to the vibrator levers so that any adjustment on the part of the pattern cylinder which would change the position of the vibrator levers may be at-

tended by a corresponding movement of the knife.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a front elevation of a Knowles head having my invention applied thereto,

Fig. 2 is a vertical section looking in the direction of arrows 2—2, Fig. 1, certain parts being omitted,

Fig. 3 is a top plan view looking in the direction of arrow 3, Fig. 2, showing one of the knife supporting rods,

Fig. 4 is a front elevation of the lock knife showing its relation to the vibrator levers, and

Fig. 5 is a horizontal section along line 5—5 of Fig. 2.

Referring to the drawings, I have shown a loom frame 10 in which are journaled upper and lower oppositely rotating mutilated actuating cylinders 11 and 12, respectively. A heel pin 13 supports a plurality of vibrator levers 14 on each of which is rotatably mounted a vibrator gear 15. The latter is located between the cylinders and is either raised or lowered depending upon the call of the pattern. The latter is determined by the pattern chain 16 which is mounted on shaft 17 supported on stands 18 which may be bolted to the loom frame.

Each vibrator gear has pivoted thereto a harness connector 19 which may be attached to a harness jack 20. The latter may be pivoted in the usual manner to the loom frame and have connection in any approved manner with the harnesses of the loom.

By connections not shown the cylinders are caused to rotate as described and the pattern cylinder rotates to place a new pattern

surface under the vibrator levers each pick of the loom. When a vibrator lever is to be raised a ball will appear thereunder so that the associated vibrator gear will be operatively disposed with respect to the top cylinder 11. In like manner, when the vibrator lever is to be in down position a so-called sinker or ball of small diameter will appear thereunder so that the vibrator gear may fall to a position 10 where it will be engaged by the lower cylinder 12.

A fixed comb 21 has projecting through the upper end thereof the right ends of the vibrator levers as viewed in Fig. 1, each of said 15 vibrator levers having a projecting tip 22 having inclined upper and lower surfaces 23 and 24, respectively, as shown in Fig. 4. A comparatively sharp knife edge 25 lies between these inclined surfaces.

20 Said tips have horizontal upper and lower surfaces 26 and 27, respectively, which engage the lock knife 28. The latter may have a rounded edge 29 which is acted upon by mechanism to be described to move into and out of locking engagement with the tips.

The lock knife is mounted on a plurality of rods 30 the upper ends of which are provided with rod heads 31 slotted as at 32 to receive the lock knife 28. A bolt 33 passes 30 through each rod head and the lock knife and holds the latter in fixed position with respect to the bolt. The lower end of each rod is threaded and extends through an arm 34 pivotally mounted on a shaft 35 which is 35 pivotally mounted on a shaft 35 which is supported in the loom frame. Upper and lower check nuts 36 and 37, respectively, position the rod 30 with respect to the arm 34 so that each of said arms may be adjusted vertically with respect to the shaft 35. The 40 latter is substantially parallel to the pattern cylinder shaft 17 so that any variation in the stands 18 which would result in changing the location of the tips 22 can be accompanied by a corresponding vertical adjustment on the 45 part of the lock knife through the lock nuts 36 and 37.

One of the rods 30 has secured thereto an operating finger 40 which is adjusted thereto by means of screw 41 and said finger has a 50 slot 42, Fig. 5, which is in substantial alignment with a second slot 43 formed in the depending arm 44 of a cam lever 45. The latter carries a roll 46 which is received in a track cam groove 47 formed in a cam plate 48. The 55 latter is secured to the top cylinder 11 and rotates therewith. A power transmitting element in the form of a stud 49 is interposed between the arm 44 and the finger 40 and passes through the aligning surface, said stud 60 being vertically adjustable for the purpose of varying the extent of movement of the lock knife. The movement of the latter may also be changed by altering the location of the hub 50 of the finger 40 by means of set screw 41. 65 In operation, the top cylinder rotates pref-

erably with a continuous motion in one direction when the loom is weaving normally and the cam groove acts to oscillate the lever 45 positively in opposite directions. The cam is so arranged that the arm 44 is moved to the right as viewed in Fig. 1 when the pattern cylinder is presenting a new pattern surface under the vibration levers. This action moves the lock knife out of the path of the tips 22 so that the levers 14 may respond to the demands of the pattern without interference. As soon as the vibrator levers have assumed the position corresponding to the next shed the cam will act to move the arm 44 to the left, thereby positively moving the lock knife 80 toward the tips. This action preferably precedes engagement of the vibrator gears with the mutilated actuating cylinders. The cam is so designed as to hold the lock knife to the left as viewed in Fig. 1 during the time that the vibrator gears are being rotated. As soon as their movement is completed the cam will act to move the lock knife positively to the right away from the tips so that the levers 14 may again respond to the demands of the 90 next succeeding shed.

As previously suggested if the lock knife does not align accurately with the tips 22 because of the fact that it is not strictly parallel to the pattern cylinder shaft 17, the vertical position of the rods 30 may be adjusted to bring about the proper alignment, after which the stud 49 can be adjusted to insure proper inward movement toward the tips 22 on the part of the lock knife 28. There is sufficient clearance in the device to permit the lock knife to move out of engaging position with the vibrator levers to any one of several outward positions. It is not so essential to be able to position accurately the outward or right hand movement of the lock knife, and this fact makes it possible by the structure set forth to give the lock knife its proper inward movement. The setting should be such that the horizontal flat upper and lower surfaces of the lock knife should be permitted to engage the surfaces 27 and 26, respectively, when the lock knife is in its full inward position.

A feature of my present invention which so far as I am aware has not existed in previous constructions of this type resides in the fact that the lock knife is given a positive inward movement toward the vibrator levers. It occasionally happens that a vibrator lever will not be perfectly straight and will have sufficient frictional contact with a neighboring lever so that when the latter is raised the bent lever will rise slightly. Under such conditions the upper inclined surface 23 will be out of alignment with the corresponding surfaces of the lowered vibrator levers and as the lock knife moves inwardly its downward surface will engage the part 23 of the slightly raised vibrator lever and depress the same to 125

its proper position. Heretofore springs have been employed for accomplishing the inward movement of the lock knife and they have not always been sufficiently strong to give the vibrator levers their proper setting. It has also been found in certain instances the continual stretching and contraction of the aforesaid springs results in their breakage and causes the lock knife to be given a positive outward movement but no positive inward movement, thus the vibrator levers will not be locked or moved to their proper position when the spring breaks and the defective operation of the head motion will result.

From the foregoing it will be seen that I have provided an improved form of lock knife for Knowles heads wherein positive locking and unlocking movements are given to the lock knife. The lock knife and the vibrator tips are preferably so formed that the positive inward movement will result in moving a vibrator lever either to its full up or down position. In previous constructions where a yielding element has been relied upon to move the knife to locking position a misplaced vibrator lever could overcome the effect of the spring and prevent the knife from moving to locking position. A mispick might result under these conditions but the loom would continue to run and a change in the pattern might prevent a repetition of the mispick with sufficient frequency to insure its protection. Furthermore, the parts are so related that they may be adjusted to bring about alignment with the lock knife with the tips 22, and the extent of motion may be varied by the stud 49 which is placed in a readily accessible position.

Having thus described my invention it will be seen that changes and modifications may be made therein by those skilled in the art without departing from the spirit and scope of the invention and I do not wish to be limited to the details herein disclosed, but what I claim is:

1. A harness operating device having a pair of spaced actuator cylinder gears between which extend movable vibrator levers, a lock knife to engage and restrain movement of the vibrator levers, a pivot about which the lock knife moves, an actuating lever for the lock knife extending toward the pivot of the lock knife, a second pivot about which the lever moves, operative connections between the lever and the lock knife, and means to move said operative connections to assume any one of a plurality of positions between said pivots.

2. A harness operating device having a pair of spaced actuator cylinder gears between which extend movable vibrator levers, a lock knife to engage and restrain movement of the vibrator levers, a pivot about which the lock knife moves, an actuating lever for the lock knife, a second pivot about which the lever

moves, operative connections between the lever and the lock knife, and means to cause said connections to assume any one of a plurality of positions at different distances from one of the pivots.

3. In a harness controlling mechanism operating with spaced rotating cylinder gears, and a set of vibrator levers to be operatively positioned with respect to the cylinders by a pattern mechanism, a lock knife common to all the vibrator levers, a track cam moving with one of the cylinders and a cam lever moved in opposite directions positively by the cam and operatively related to the lock knife and effective to give the latter movements independent of and subsequent to positioning of the vibrator levers by the pattern mechanism.

4. In a harness controlling mechanism operating with spaced rotating cylinder gears, and a set of vibrator levers to be operatively positioned with respect to the cylinders by a pattern mechanism, a lock knife common to all the vibrator levers, a track cam rotating with one of said cylinders, a cam lever operatively related to the cam and moved thereby positive in opposite directions, a frame for the lock knife, and connections between the frame and the lever effective to transmit positive forces from the said lever to the lock knife toward and away from locking position, said cam effective independently of the pattern mechanism to move the lock knife into locking position subsequent to the positioning of the vibrator levers by the pattern mechanism.

5. In a harness controlling mechanism operating with spaced rotating cylinder gears, and a set of vibrator levers to be operatively positioned with respect to the cylinders by a pattern mechanism, a lock knife common to all the vibrator levers, a track cam moving with one of the cylinders, a cam lever operatively related to the cam to be given positive movements by the cam in opposite directions, a lock knife frame movable about a pivot removed from the pivot of the cam lever, and connections between the cam lever and the frame, the cam being effective after the pattern mechanism has positioned the vibrator levers to move the lock knife into locking relation with respect to said vibrator levers.

6. In a harness controlling mechanism operating with spaced rotating cylinder gears, and a set of vibrator levers to be operatively positioned with respect to the cylinders by a pattern mechanism, a lock knife common to all the vibrator levers, a track cam moving with one of the cylinders, a cam lever operatively related to the cam to be given positive movements by the cam in opposite directions, a lock knife frame movable about a pivot removed from the pivot of the cam lever, and connections between the cam lever and the frame, the cam being effective after the pat-

tern mechanism has positioned the vibrator levers to move the lock knife into locking relation with respect to said vibrator levers, said connections including a part normally fixed to but movable to different positions relatively to the lock knife frame, said part to be operatively related to the cam lever to vary the amount of movement of the lock knife.

- 10 In testimony whereof I have hereunto affixed my signature.
